UNITED STATES PATENT OFFICE.

ARTHUR McDougall DUCKHAM AND JOHN STANLEY MORGAN, OF LONDON, ENGLAND, ASSIGNEES TO THERMAL INDUSTRIAL AND CHEMICAL (T. I. C.) RESEARCH COMPANY LIMITED, OF LONDON, ENGLAND, A BRITISH COMPANY.

METHOD OF HEATING MATERIAL AT SUCCESSIVELY DIFFERENT TEMPERATURES.

Application filed August 8, 1921. Serial No. 491,021.

To all whom it may concern:

Be it known that we, ARTHUR McDougall DUCKHAM and JOHN STANLEY MORGAN, both subjects of the King of Great Britain, residing in London, England, have jointly invented a certain new and useful Improved Method of Heating Material at Successively Different Temperatures, of which the following is a specification.

- 10 10 A known process of subjecting a material to heat treatment by contact with a molten metal consists in causing the material to travel between a surface of the molten metal and a solid surface wholly or partly submerged in the molten metal. Sometimes the solid surface travels with the material, as when the material is caused to enter the re-entrant angle between the surface of the metal and the surface of a 20 drum revolving partly submerged in the molten metal. Sometimes the solid surface is stationary and inclined, so that the material, introduced beneath the lower end of the surface, travels upwards along the surface owing to the fact that the material is 25 specifically lighter than the molten metal. By the present invention heat treatment of the material is conducted in successive steps by causing the material to travel repeatedly through molten metal as above described and to acquire a different temperature at each passage.

When a single bath of molten metal is used and the successive temperature steps are attained by varying the time during which the travel occurs, the time of travel in each stage wherein the temperature to be attained is lower than the temperature of the molten metal, must be insufficient to permit the material to attain the temperature of the molten metal, and must be adjusted so that it is only sufficient to permit the material to attain the desired temperature.

45 The invention is illustrated in the accompanying drawings.

Fig. 1 is a longitudinal section through a number of stills arranged for the fractional distillation of tar oil. The form of still has been described in the application for United States Letters Patent of John S. Morgan, Serial No. 490,650.

Fig. 2 is a plan and Fig. 3 a cross-section of Fig. 1.

Fig. 4 is a view similar to Fig. 1 of a modification, and in plan it resembles Fig. 2.

Referring to Figs. 1 to 3, the stills *a* are set in the flue of a furnace *b*. This flue is divided into an upper and lower flue by a partition *c* and there is a by-pass flue *d* putting the upper and lower flue into communication with each other at one end of each still. The upper flue alone communicates with the furnace so that the proportion of heating gases passing along the lower flue is determined by the degree to which the valves *e* in the upper flue in front of each flue *d* are open. It will be seen that by suitable adjustment of these valves and of the corresponding valves *f* in the lower flue, the temperature of the several stills may be varied.

The oil is fed by pipe *g* into the still furthest from the furnace (and therefore at the lowest temperature) and is carried beneath the surface of the molten lead *h* by the revolving drum *i*. It leaves the still by pipe *k* to flow to the next still, and so on throughout the series, the residue being discharged by pipe *l*. The volatile constituents expelled in each still are collected separately from the necks *m* in well-known manner.

In the modification shown in Fig. 4 the material travels repeatedly through the same lead bath but at a different speed at each travel, thereby attaining a different temperature at each passage through the metal. In this case the stills *o* are without rigid bottoms, the lead bath *p*, common to them all, serving the function of a bottom to each still. In other respects the stills are constructed as already described and the tar oil flows through them in the manner already described. Each of the cylinders *i*, however, is rotated at a different speed, the speed decreasing from one end of the series to the other and being most rapid in the end still into which the oil is fed and from which the constituents of lowest boiling point are collected.

Since all the stills are at the same temperature the lead bath *p* is set directly in the flue *n* of the burner *b*.

The rate of rotation of each drum or cylinder is such that, in each stage, the time during which the material passes be-

tween the surface of the drum and the molten metal is only sufficient to permit the material to attain the temperature desired for that stage.

5 The invention is particularly suitable for fractional distillation whether of liquid or solid material. As an example of the latter the destructive distillation of wood may be mentioned, there being considerable advantage in heating the wood in successive stages for obtaining the best yield of the several products.

Having thus described the nature of the said invention and the best means we know 15 of carrying the same into practical effect, we claim:—

1. A process of heating a material at successively different temperatures for the purpose of fractionally vaporizing constituents 20 thereof, which consists in causing the material to travel between a solid surface immersed in a bath of molten metal and a surface of the molten metal, removing the constituents volatilized by the treatment,

and causing the unvolatilized portions of 25 the material to travel between another such solid surface and a surface of molten metal and to acquire a different temperature at each passage.

2. A process of heating a material at successively different temperatures for the purpose of fractionally vaporizing constituents thereof, which consists in causing the material to travel in a bath of molten metal 30 having a given temperature, between a solid surface immersed in said bath and a surface of the molten metal, removing the constituents volatilized in the bath, and causing the unvolatilized portion of the material to pass into another bath of molten 35 metal having another given temperature and there to travel between another solid surface immersed therein and a surface of the molten metal.

In testimony whereof we have signed our 40 names to this specification.

ARTHUR McDougall DUCKHAM.
JOHN STANLEY MORGAN.
